UNITED STATES PATENT OFFICE.

RICHARD F. JONES, OF ST. LOUIS, MISSOURI.

ELECTRIC-ARC LAMP.

SPECIFICATION forming part of Letters Patent No. 355,172, dated December 28, 1886.

Application filed August 7, 1886. Serial No. 210,334. (No model.)

To all whom it may concern:

Be it known that I, RICHARD F. JONES, a citizen of the United States, residing at the city of St. Louis, in the State of Missouri, 5 have invented a certain new and useful Improvement in Electric-Arc Lamps, of which the following is a full, clear, and exact description, reference being had to the accompanying drawings, forming part of this specification, 10 and in which—

Figure 1 is an elevation of my improved lamp. Fig. 2 is an elevation of the lamp, showing another side from that shown in Fig. 1. Fig. 3 is a horizontal transverse section taken on line 3 3, Fig. 2, looking downward. Fig. 4 is a similar view looking upward. Fig. 5 is an enlarged detail vertical section taken on line 5 5, Fig. 2. Fig. 6 is a horizontal transverse section taken on line 6 6, Fig. 1. Fig. 20 7 is an enlarged horizontal detail section taken on line 7 7, Fig. 1. Fig. 8 is a vertical section taken on line 8 8, Fig. 7.

The present invention relates to improvements on Letters Patent granted to myself 25 September 15, 1885, No. 326,123; and the principal object of my present invention is to provide a means for holding and feeding the respective carbons, and a means, so far as the upper carbon is concerned, that will give a 30 constant bearing upon the carbon and avoid an objection to my former patent of a space being left at times when the carbon feeds between the carbon and the clamps or levers; and, so far as the lower carbon is concerned, 35 my present invention relates to a mechanism which will insure a uniform pressure upon the carbon regardless of irregularities in its size or diameter.

My present invention consists in features of 40 novelty hereinafter fully described, and pointed out in the claims.

Referring to the drawings, A represents the frame of the lamp.

B represents the upper carbon, and B' the 45 lower carbon.

C represents a tube through which the upper carbon is fed and in which it is held, and C' represents a tube through which the lower carbon is fed and in which it is held. 50 Surrounding the tube C is a sleeve, D, provided with arms D', similar to those in my former

patent already referred to, and, as in my former patent, there is pivoted to the lower ends of these arms levers E, provided with counterbalances or weights E'. In my former patent 55 the inner ends of these levers were constructed to bear directly against the carbon. The effect of this was that when they were acted upon by the magnets to release the carbon there would be a space left between the carbon and each lever, which resulted in the electric current arcing across from the lever to the 60 carbon, which was found objectionable, in that the carbon and ends of the levers would be burned. To avoid this I have pivoted to the 65 arm D' a clasp, F, which is made in two parts, as shown, each part being pivoted to one of the arms D', as shown in Fig. 1. Each part is made $\backslash$ -shaped on its inner surface to form a bearing for the carbon, and the two parts 70 form substantially a divided sleeve with a space left between them. They are preferably pivoted to the arms D' by links F', so as to allow them to spring outward freely when the levers E are operated and permit the downward feed of the carbon. It will thus be seen 75 that with this arrangement there will always be a contact between the carbon and the clasp F, for at no time is the clasp swung out sufficiently far to be removed out of contact with the carbon, but only sufficiently to allow the carbon to slip through.

G represents the vertical rods, which are pivoted at their lower ends to lever E, and pass through an opening in plate H, and are 85 attached to bar G.

I have shown in this application two helices having movable armatures or cores I, arranged vertically and secured to the top of the frame A.

The plates H are connected to the cores in this instance by a plate, H', and a bar, J, the bar being pivoted at its outer end to the frame of the lamp at J', and which is provided with a cross head or bar, J'', to which the plates 90 are made fast by links J''. The inner end of the bar is made fast at H' to the plate H', which is secured to the cores. The bar has a socket through which the tube C passes loosely. It will now be seen that when the current is 95 turned on the raising of the cores or armatures I will lift the rods G through means of the 100

plates H, which grip the rods G by their free ends hanging down and not being lifted with their short ends, the two members H and G thus binding upon each other. The lifting of rods G causes the inner ends of levers E to compress the clasp F, which in turn grips the carbon, thus raising said carbon to form the arc, the sleeve D sliding on the tube C. When the core or armature falls, the set-screws Z in 10 the free ends of plates H come against the cross-piece A' of the lamp and prevent the free ends of the plates H from moving downward, which at one releases the rods G, and their weight causes the levers E to allow the clasp F to 15 loosen its grip on the carbon, which then feeds downward, and as soon as the core rises the clasp is caused to grip the carbon again, holding it from moving too far, and thus a constant feed is kept up. It will now be understood how the rise and fall of the cores 20 will operate the levers E and through means of the clamp F control the feed of the carbon.

The lower carbon is supported in its tube from beneath in the same manner as in my patent referred to—that is to say, by means of a plate, L, connected to counter-weights L' by ropes or cords L'', passing over pulleys L'', one of which should be made of some non-conducting material, to prevent the passage of the 30 electric current from one side of the lamp to the other; or, instead of one of these pulleys being made of non-conducting material, other means could be provided to insulate one side of the lamp from the other.

35 The part of my present invention relating to the means operating upon the lower carbon consists of a dog, M, in the form of a lever, pivoted at M' to a projection, M'', extending outward from a collar, M'', formed upon or secured to the tube C'. The inner end of this dog bears against the carbon and holds it from upward movement under the influence of the weights L' until it is released by the descent of the cores. The dog is held into contact 45 with the carbon by means of a spring, N, secured to the projection M'', and bearing against the outer end of the dog.

It will be seen that when any irregularities in the carbon come opposite the dog the latter will be constantly held against the carbon by the spring. To insure a uniform action of the dog on the carbon each time the cores descend, I have provided the following means:

55 O represents a yoke, between which the outer part of the dog M fits, and the inner ends of which have inclined notches O', receiving the pin M', that connects the dog M to the projection M''. The outer end of this yoke has a 60 ratchet-tooth, O'', that engages the teeth of a rack, M'', on the outer end of the dog M. Secured to the outer end of the yoke is a rod, P, that extends upward and is connected to a bar, P', pivoted at P'' to the frame of the lamp, and jamming at its inner end by means of a rod, P'', against the plate H''. The rod P'' has jam-nuts P' on its upper end, which are held

against the plate H'' by a spring, P'. Now, when the plate H'' and cores fall, it will be seen that the outer end of the yoke O will be 70 depressed, and as it is depressed the inner end of the dog M will be released from the carbon.

In order that the action of the yoke upon the dog will always be the same regardless of the position of the dog before mentioned, caused 75 by irregularities in the carbon, the yoke is so constructed that when the spring N lifts the dog it will move outward, allowing the tooth O'' to be disengaged from the notch it occupies, and this movement of the yoke is provided for by means of the inclined notches O' in the inner end of the yoke, that fit over the pin M''. Thus, when the yoke is lifted, a vertical movement of it will take place, (owing to the inclined notch bearing on the pin,) and 80 the tooth will thus be made to engage the rack at the same horizontal point when the yoke again descends.

To assist the cores in supporting the collar D, arms D', and parts attached thereto, I locate springs U between the base-plate of the frame and nuts on the upper ends of rods W, as shown in Fig. 2. The rods W extend upward from the arms D' through the base-plate of the frame, and the springs U preferably surround these rods, as shown.

It has been found at times that an electric current would arc across from the upper tube of the lamp to the carbon. To avoid this difficulty I have placed insulations Y between the 100 frame and the tube, as shown in Fig. 2.

I claim as my invention—

1. In an electric-arc lamp, the combination of the levers for grasping the upper carbon, a clasp located between the inner ends of the 105 levers and the carbon, rods connected to and extending upward from the levers, and means for operating said levers electrically, substantially as set forth.

2. In an electric-arc lamp, the combination 110 of the pivoted clasp, levers for engaging the clasp and pressing it against the carbon, and means for operating the levers, substantially as and for the purpose set forth.

3. In an electric-arc lamp, the combination 115 of the pivoted two-part clasp, levers bearing, respectively, against the two parts of the clasp, and means for operating the levers, substantially as set forth.

4. In an electric-arc lamp, the combination 120 of the tube for receiving the upper carbon, arms secured to the tube, clasp pivoted to the arms and bearing against the clasp, and means for operating the levers, substantially as set forth.

5. In an electric-arc lamp, in combination 125 with the tube for receiving the carbon, arms connected to the tube, levers connected to the arms, clasp connected to the arms, rods extending upward from the arms and levers, plate 130 connected to the upper ends of the arms, rods, springs located around the rods, and means for operating the plate electrically, substantially as set forth.

6. In an electric-arc lamp, in combination with the tube for holding the upper carbon, arms connected to the lower end of the tube, clamp connected to the arms, levers connected to the arms, rods connected to the levers, and spring-plate connected to the arms, rods, and means for operating the plate electrically, substantially as set forth.
- 5 7. In an electric-arc lamp, the combination of the pivoted clasp, levers for engaging the clasp and pressing it against the carbon, and means for operating the levers, the inner surface of the clasp being formed of \ shape, substantially as and for the purpose set forth.
- 10 8. In an electric-arc lamp, the combination of the tube for holding the lower carbon, spring-
- dog pivoted to the tube, yoke embracing the dog and having ratchet connection therewith, and means for operating the yoke electrically, substantially as set forth.
- 20 9. In an electric-arc lamp, the combination of the tube for holding the lower carbon, spring-dog pivoted to the tube, yoke having inclined notches at its inner end fitting over a securing-pin, rack on the outer end of the dog, ratchet-tooth on the yoke, engaging the rack on the dog, and means for operating the yoke electrically, substantially as set forth.

RICHARD F. JONES.
